UNITED STATES PATENT OFFICE.

GEORGE E. STARR, OF SAN FRANCISCO, CALIFORNIA.

DESIGN FOR A TIRE.

44,735.

Specification for Design.

Patented Oct. 14, 1913.

Application filed February 6, 1912. Serial No. 675,873. Term of patent 14 years.

To all whom it may concern:

Be it known that I, GEORGE E. STARR, a citizen of the United States, residing at San Francisco, in the county of San Francisco and State of California, have invented a new, original, and ornamental Design for Tires, of which the following is a specification, reference being had to the accompanying drawing, forming part hereof.

In the drawing, Figure 1 is a top elevation of a tire showing my new design; and Fig. 2 is a side elevation thereof.

I claim:

The ornamental design for a tire, as shown.

GEORGE E. STARR.

Witnesses:

MARY F. ALLEN,
W. LINN ALLEN.
